UNITED STATES PATENT OFFICE.

WILLIAM DIETZEL, OF MERRICK, NEW YORK.

PLATING MACHINE.

Application filed February 18, 1920. Serial No. 359,638.

To all whom it may concern:

Be it known that I, WILLIAM DIETZEL, a citizen of the United States, and a resident of Merrick, county of Nassau, and State of New York, have invented a new and Improved Plating Machine, of which the following is a full, clear, and exact description.

This invention relates to a machine for treating articles to be plated, and has for an object the provision of a construction which is specially adapted for plating small articles deposited in the machine but capable of acting as a pickling machine.

Another object of the invention is to provide an improved construction utilizing a spiral trough for tumbling articles during plating, so that a continuous operation may be performed and articles may be continuously fed in at one end and discharged at the other end completely plated.

A still further object of the invention is to provide an improved plating machine in which the articles to be plated are fed in at one end in an unplated condition, and discharged at the opposite end in a plated condition with means interposed between the ends for causing the articles being plated to remain in substantially the richest part of the plating solution as the articles move from one end of the machine to the other.

In the accompanying drawing;—

Figure 1 is a top plan view of a plating machine disclosing an embodiment of the invention;

Figure 2 is an end view of the machine shown in Figure 1;

Figure 3 is a transverse sectional view through Figure 1 on the line 3—3;

Figure 4 is a longitudinal, vertical, sectional view through Figure 1 on the line 4—4;

Figure 5 is a detail fragmentary, longitudinal, sectional view through one of the journals shown in Fig. 4 and a gear wheel connected therewith illustrating how the central shaft is insulated from its driving member;

Figure 6 is a detail fragmentary, sectional view through Figure 7 on the line 6—6;

Figure 7 is a detail fragmentary sectional view through the discharge end of the conveyor shown in Fig. 1 the same to be taken on the line 7—7 of Figures 1 and 6;

Figure 8 is a view similar to Figure 7, but

showing the discharge end of the conveyor as it is leaving the plating solution; and

Figure 9 is an enlarged detail fragmentary sectional view illustrating how the contact strip in the conveyor is held in place.

Figure 10 is a detail fragmentary view showing a modified form of contact strip for the trough.

Figure 11 is a view similar to Figure 10, but showing a further modified form of contact strip.

Referring to the accompanying drawing by numerals, 1 indicates an ordinary tank formed of wood or other desirable material, designed to receive the plating solution. 2. 70 This tank or vat 1 is provided with an angle iron facing 3 on which the journal boxes 4 and 5 are mounted, said journal boxes accommodating the main or central shaft 6. This shaft is insulated from the facing 3 as 75 illustrated in Fig. 5 while allowing the shaft to freely rotate. It will be noted that a suitable insulation 8 is provided in the bearing boxes 4 and a separate insulation 9 is arranged interiorly of the hub of a gear wheel 10. A suitable set screw or fastening means 11 is provided for clamping the gear wheel 10 rigidly to the shaft 6. The journal box 5 is also insulated similar to the journal box 4. The gear wheel 10 continually 80 meshes with a pinion 12 which is connected rigidly to a worm wheel 13 in any desirable manner as for instance, being rigidly secured to a shaft 14, and said shaft in turn 85 being rigidly secured to the worm wheel 13. The shaft 14 may be supported in any desirable manner, as for instance by suitable brackets secured to the tank 1. A worm 15 is provided which continually meshes with the worm wheel 13, said worm having a 90 shaft 16 supported in suitable bearing members connected with the tank 1. The shaft 16 carries a pulley 17 at one end as shown in Figure 1, so as to receive power from a belt or other suitable source of power. It 95 will be noted that the arrangement of gears is such that the shaft 6 is geared down to a large extent so that the shaft 6 will rotate comparatively slowly as shown particularly in Figures 1 and 4. A spiral trough 18 is 100 rigidly secured to the shaft 6 so as to rotate therewith, and this trough may be constructed of any desirable material and be of any desired shape in cross section, that shown being rectangular. The trough car-

ries an insulating liner 19 for its full length, said liner being secured in place in any desirable manner as for instance by a number of bolts 20. The bolts 20 also pass through 5 a contact plate 21 but is insulated from the metal parts of the trough 18. The forward end or intake end of the trough 18 is provided with an annular metallic ring 22 which ring is connected to the contact strip 10 21 by metallic connectors although said connectors in the ring are insulated from the metallic parts of the trough 18. A brush 23 is mounted on the facing strip 3 but is insulated therefrom, said brush being 15 mounted so as to be swung into and out of engagement with the ring 22. A chute or inlet trough 24 is supported on the vat 1 by any desired means as for instance brackets 25, said trough being covered at its 20 inner end and formed with a downward extending passageway 26 so as to discharge positively into the trough. An electrical conductor 27 is connected with the brush 23 in any desired manner and a second electrical conductor 28 is connected in any desired manner to a rod 29, which rod is insulated from the facing strip 3 and is provided with an inner end 30 continually in 25 electrical contact with the shaft 6. By this construction and arrangement, electric current may pass in through the conductor 27 to the brush 23, from the brush 23 to the contact strip 21, into the solution 2 and thence pass through an anode 31. This 30 anode is connected with a suitable hook or other support 32 supported by the shaft 3 between suitable stops 33. The current passing from the anode 31, passes through the hook 32 on to the shaft 6, and thence to the 35 end member 30, rod 29 and to the conductor 28. When there is an article or a number of articles in the trough, the current will pass from the strip 21 to said articles, and thence into the solution before it 40 reaches the anode 31. By this action some of the metal content in the solution will be deposited on the articles to be plated. It will be observed that the trough 18 is rigidly secured to the shaft 6 through 45 a suitable bracket 34, which is riveted or otherwise secured to the trough, said bracket carrying a post 35 having a bearing member 36 clamped to the shaft 6. A suitable insulating sleeve 37 is interposed so that there 50 will be no electrical connection between the shaft and the trough at this point.

In operation, the articles to be plated are fed into the trough 18 through the chute 24 as the trough rotates in the direction of 55 the arrow 38 shown in Figure 1. The articles being plated are gradually forced along the trough from one end to the other under the action of gravity and by reason of the shape of the trough. As the trough rotates, the articles will gradually tumble

to the bottom and in fact will continue to tumble under the action of gravity so as to remain substantially at the bottom of the trough. This will cause a gradual longitudinal movement of the articles from one end of the trough to the other, and the current passing through the machine will produce a plating action as the articles are thus moved. When the articles reach the discharge end of the trough, they are in 70 a certain sense scooped up on the turned over end section 39 (Figures 1 and 7). This section is provided with a number of perforations 40 to permit the solution to drain freely therefrom while holding the plated articles. As this turned over or scooped end passes the central upper position, the articles plated and carried by said end are forced by gravity on to a discharge platform 41 and from thence by gravity to a 75 discharge chute 42, which chute is supported in any desired manner on the vat 1. In this way upon each revolution of the trough, a certain quantity of plated articles will be discharged automatically. It will be noted that after the articles are fed into the machine at one end, they are not touched or in any way operated on by the operator until after they have been discharged on to the chute 42. The article discharged on the chute 42 may be received by a traveling belt or receiving device so as to be later buffed or otherwise treated as desired. It will be observed that the anodes 31 extend 80 into the solution adjacent the bottom of the trough at different points, so that the solution is enriched at the point where the articles being plated must pass. In this way the matter being deposited on the articles being plated is merely transferred from the anodes to said articles and the solution 85 90 95 100 105 110 115 120 125 130 135 140 145 150 155 160 thereby produces an even plating action over the entire article.

What I claim is:

1. A plating machine comprising a solution carrying vat, a spiral article carrying member substantially U-shaped in cross section, rotatable means for operating said article carrying member so that the same will transport said articles through said solution from adjacent one end of the vat to adjacent the opposite end, means for enriching the solution in a line adjacent the path traveled by said articles, and means for causing an electrical current to pass through said articles as the articles travel.
2. A plating machine comprising a vat for containing a solution, a spirally constructed trough arranged so that part will be submerged in said solution, means for rotating said shaft continually during plating operations, means for directing articles to be plated into said trough near one end, said trough having a bucket shaped turned over portion at the opposite end, said portion being perforated whereby it will gather the articles as they approach the end while allowing the solution to escape, a chute for automatically discharging said articles from said turned over portion, and means for supplying electrical current to said articles as they are moved by said trough.
3. In an electro-plating device, a spiral trough formed with an inlet at one end and a discharge opening at the opposite end, a roughened contact strip arranged in the bottom of said trough extending from one end to near the opposite end, and means for passing a current of electricity through said contact strip during the plating operation.
4. In a plating machine of the character described, a spirally constructed trough formed with an inlet at one end and an outlet at the opposite end, said trough being formed roughened or irregular on the bottom so that the solution used may come in

contact with articles sliding or tumbling over said bottom.

5. In a plating machine of the character described, a spiral trough formed with an insulation on the interior surface, a metallic strip mounted on said insulation on the bottom of the trough, said strip being corrugated so as to expose all parts of an article passing thereover as they are moved along.

6. In a plating machine of the character described, a spirally constructed trough, means for rotating said trough, an insulating member in the interior of said trough, a roughened contact strip mounted in the bottom of said trough, an annular contact ring electrically connected with said strip, and a stationary member for connecting said ring with a source of electrical energy.

7. In an electrical plating device, a spiral trough formed with an inlet at one end and a bucket shaped portion at the opposite end, provided with a discharge chute positioned to receive the article from said last mentioned end and discharge the articles under the action of gravity from the trough.

8. In a plating machine of the character described, a spiral trough formed with an insulation on the interior surface thereof, and a metallic strip mounted on said insulation on the bottom of the trough substantially for the full length of the trough so that articles placed in the trough will be in continuous contact with said strip as they are moved along.

9. In a plating machine of the character described, a spirally constructed trough, an insulating member in the interior of said trough, a metallic strip arranged in said trough, an annular contact ring arranged adjacent one end of said trough, means for electrically connecting said ring with said strip, and a brush member for connecting a source of electrical energy with said ring.

WILLIAM DIETZEL.
